INVENTOR.

Harold V. McIntosh
BY Whittmore Hubbard
Whittmore & Delknap
ATTORNEY'S

UNITED STATES PATENT OFFICE.

HAROLD V. MCINTOSH, OF DETROIT, MICHIGAN.

WARM-AIR FURNACE.

Application filed May 2, 1921. Serial No. 466,196.

To all whom it may concern:

Be it known that I, HAROLD V. MCINTOSH, a subject of the King of Great Britain and Ireland, residing at Detroit, in the county of Wayne and State of Michigan, have invented certain new and useful Improvements in Warm-Air Furnaces, of which the following is a specification, reference being had thereto to the accompanying drawing.

10 The invention relates to warm air furnaces and has for its object the provision of an improved dome section provided with means for tumbling or deflecting the incompletely burned volatilized products of combustion inwardly toward the center of the dome section and for increasing the radiating surface over which the air to be warmed passes. Other objects of the invention reside in the novel features of construction 15 and combinations and arrangements of parts 20 and as more fully hereinafter set forth.

In the drawing:

Figure 1 is a longitudinal central section through a portion of the furnace embodying 25 my invention;

Figures 2 and 3 are respectively side and front elevations of the dome section.

1 is the fire pot of the furnace, and 2 the combustion chamber including the dome section 3 and the upper portion 4 of a casing 5 between which and the dome section passes the air to be warmed.

The dome section 3 has the upper portion 6 thereof tapering from the bottom toward 35 the top and provided with the outlet opening 7 at the top. The upper portion 6 of the dome section is provided with the substantially horizontal rows of outwardly extending projections 8, which are hollow on their 40 inner sides to form the recesses 9. These recesses have the rounded substantially horizontal top walls 10 and taper in width as well as increase in depth from their bottoms toward their tops. The bottoms of the 45 recesses are substantially flush with the inner surface of the upper portion of the dome section, the arrangement being such that unequal expansion of the wall is avoided.

For the purpose of tumbling or deflecting 50 inwardly all of the incompletely burned volatilized products of combustion which upon leaving the fire pot 1 pass upwardly along the upper portion of the dome section, the recesses of the different rows alternate 55 vertically, so that any of the products of

combustion passing the recesses of the first row will enter the recesses of the next row. The products of combustion upon entering a recess converges as it moves upwardly and finally is tumbled or deflected laterally inward toward the center of the dome section, where they are commingled with the burning products of combustion and is burned. Since there are a plurality of rows of recesses and 60 since the dome section tapers from the bottom toward the top, it is seen that if some of the incompletely burned volatilized products of combustion pass beyond the recesses of the lower row and also pass the recesses of 65 the second row, they will engage in the recesses of the next row and be commingled with the burning products of combustion.

Due to the fact that there are a plurality of rows of outwardly extending projections 9 on the wall 6 of the fire section, the heat 70 radiating surface of the wall is materially increased so that eddies are produced in the air passing between the furnace casing and the dome section, and this air is uniformly 75 heated.

What I claim as my invention is:

1. In a furnace, a dome section having a plurality of staggered upwardly tapering recesses formed in its wall, said recesses tapering in width and increasing in depth from 80 their bottoms toward their tops, the bottoms of said recesses being substantially flush with the inner surface of the dome wall.

2. In a furnace, a dome section having a 85 plurality of horizontal rows of spaced upwardly tapering recesses formed in its wall, the spaced recesses of one row alternating with the spaced recesses of the adjacent row.

3. In a furnace, a dome section having a 90 plurality of horizontal rows of spaced staggeredly arranged tapering recesses formed therein, said recesses terminating at one end in rounded substantially horizontal walls.

4. In a furnace, a dome section having a 95 plurality of staggeredly arranged upwardly tapering recesses formed therein, said recesses terminating at one end in rounded substantially horizontal walls.

In testimony whereof I affix my signature.

HAROLD V. MCINTOSH.
